UNITED STATES PATENT OFFICE.

OTTO R. G. MUHLENBRUCH, OF DECATUR, ILLINOIS.

GAUNTLET GLOVE.

Application filed November 20, 1920. Serial No. 425,485.

To all whom it may concern:

Be it known that I, OTTO R. G. MUHLENBRUCH, citizen of the United States, residing at Decatur, in the county of Macon and State of Illinois, have invented certain new and useful Improvements in Gauntlet Gloves, of which the following is a specification, reference being had therein to the accompanying drawing.

10 This invention relates to improvements in gloves, and has for its object the provision of a gauntlet type of glove wherein the gauntlet may be detached from the hand covering portion of the glove to enable its 15 use in connection with other hand covering portions.

The primary object of the invention is to save expense to the user of gauntlet gloves by permitting the same pair of gauntlets to 20 be used on successive pairs of hand covering portions, it being well recognized that much waste has been encountered in the past by the discarding of gauntlets as an incident to the wearing away of the hand covering 25 portion, which latter always becomes impaired or worn out long before the gauntlet.

The detachability of the gauntlet with reference to the hand covering portion also adapts the gauntlet for use with various 30 types of hand covering portions, for example, light or heavy, dependent upon the desirability under changing weather conditions or character of use.

The preferred embodiment of the invention 35 comprises a wristless hand covering portion associated with a gauntlet of the usual stiff or heavy character relative to the material of the hand covering portion, the gauntlet carrying as a part thereof a 40 "goose neck" or highly flexible intermediate or wrist portion adapted to constitute a continuation of the wristless hand covering portion, the marginal part of the goose neck and the adjoining part of the hand covering 45 portion having correlated elements permitting the two to be detachably connected to constitute the desired gauntlet glove when in service; and the gauntlet with its flexible wrist portion or goose neck, and 50 also the adjoining part of the hand covering portion being formed with aligned gores to functionally perform as a continuous flexible gore when the parts are operatively brought together.

55 The above mentioned preferred embodiment of the invention is illustrated in the

accompanying drawings forming part hereof, and the details will be readily understood from the specific description herein-after contained when read in connection 60 with such drawings.

In the drawings:

Figure 1 is an elevation of the complete gauntlet glove, the hand covering portion being shown as separated from the goose 65 neck or wrist portion of the gauntlet to better illustrate the construction.

Figure 2 is a transverse sectional view through the gauntlet taken on the line 70 A—A of Figure 1;

Figure 3 is an enlarged fragmentary vertical sectional view on the line B—B of Figure 1; and,

Figure 4 is a similar sectional view showing the hand covering portion detachably 75 secured to the flexible goose neck or wrist portion of the gauntlet.

Referring more specifically to the drawings, 1 represents a gauntlet of heavy comparatively stiff formation, formed of leather or 80 reinforced fabric folded upon itself as at 2, the opposite edges being relatively free and connected by an intervening flexible gore 3 extending longitudinally thereof to the lower edge of the gauntlet to provide 85 ease and comfort by allowing for the opening of the gauntlet and flexible adjustment thereof to the wearer. Projecting from the bottom edge of the gauntlet, as just described and carried by the gauntlet as a part 90 thereof, is a member which I have technically styled a goose neck, the same being a highly flexible intermediate or wrist portion 4, preferably of a light, flexible material, such as thin, soft leather, this neck 95 portion being of substantial length to provide ample relative freedom of movement of the gauntlet proper and the hand covering portion to be referred to.

Within the goose neck 4 and stitched 100 theretround I provide an attaching strip 5 free at its lower portion to leave a circumferential space between the same and the bottom of the goose neck or wrist portion 4, which latter when the hand covering portion 105 is in place will act as an apron overlying the hand covering portion and shed water exteriorly of the latter.

The depending or apron portion of the 110 goose neck and the adjacent or underlying part of the securing strip 5 carry complementary separable fastening elements 6 and 7,

for illustration the conventional spring ball and socket clasp, the same being intended to secure the mouth or open end part of the hand covering portion in place.

5 3' represents a gore formed in the goose neck or wrist portion 4 as a continuation of the gore 3 in the gauntlet proper.

8 represents the hand covering portion, preferably shortened with respect to the 10 conventional glove to constitute what I have termed a wristless hand covering portion, the whole being formed of a material suitable for the purpose intended, that is flexible cloth or light or heavy leather, lined or unlined as the case may be, and either of the 15 fingered or mitten type as will be readily understood by the persons skilled in this art.

In line with the little finger portion of the hand covering portion 8, I provide a 20 flexible gore, indicated at 3² adapted when the parts are assembled to constitute a continuation of and the lower terminal part of the gore previously referred to as represented at 3 and 3'.

25 Preferably the open end part of the hand covering 8 is provided with button holes 9, equal in number to the separable fasteners 6 and 7, these button holes being designed to receive the ball elements 7 when the wrist- 30 less portion of the hand covering is inserted in the space between the securing strip 5 and the depending or apron portion of the goose neck or wrist portion 4, and the spring ball elements 7 engaged after the customary 35 manner with their complemental socket members 6.

When the parts are assembled as thus pointed out I provide a gauntlet glove capable of every service expected of an article of this character, of easy adjustment, ample 40 flexibility, and of satisfactory protection to the hand, wrist and sleeve of the user.

While I have herein specially defined the details employed in the preferred embodiment of the invention it will be understood 45 that said invention may be embodied in other forms as may be embraced within the scope of the hereto appended claim.

Having thus described the invention, what I claim is:

In combination with a wristless hand covering portion, a gauntlet of relatively heavy or stiff material carrying as a part thereof a highly flexible wrist portion permitting relative movement of the hand covering portion and gauntlet proper when in use, and complemental detachable parts on the hand covering portion and the wrist portion for fastening them together, the gauntlet with its flexible wrist portion being 55 provided with a flexible gore continuing along aligned edges thereof, and the hand covering portion being similarly provided with a flexible gore to register with and constitute the terminal part of said gore. 60

In testimony whereof I hereunto affix my signature in the presence of two witnesses.

OTTO R. G. MUHLENBRUCH.
